UNITED STATES PATENT OFFICE

2,233,138

METHOD OF PREPARING CARDS AND THE
LIKE FOR SORTINGLucien L. McCart, Forest Hills, N. Y., assignor to
The McBee Company, Athens, Ohio, a corpora-
tion of Ohio

Application March 6, 1940, Serial No. 322,471

4 Claims. (Cl. 164—111)

My method relates to the preparation of cards to be sorted in accordance with Perkins Patent No. 1,544,172. In my Patent No. 2,144,412 I have illustrated an apparatus which can be employed to carry out the steps of my method, but practice has shown that many forms of apparatus can be employed for that purpose besides the one set forth in my patent above referred to such, for example, 10 as Patent No. 1,922,869.

In this specification, when I say "cards" I use the word as a convenient term to describe checks, sales slips, time cards, loose leaves, etc., and in no sense as a limitation. In accordance with 15 the Perkins patent, the cards are provided with a plurality of perforations adjacent one or more edges of the cards, each hole being located so that it may be separately slotted out to the edge. These notches or slots form a pattern which 20 refers to a single classification and by following the teachings of the Perkins patent, to which reference may be had for complete details, the cards can be sorted into a numerical, geographical, or other desired sequence. Inasmuch as 25 these notches are of many patterns, they must be exact or the card or cards will be hopelessly lost, if incorrectly notched. I invented my method of preparing the cards for sorting under such a system, and then worked out an apparatus to 30 enable me to practice the same.

My invention has for its principal object to provide a method which when followed will insure every card being correctly slotted to designate the desired classification.

35 For the purpose of illustrating a concrete form of apparatus to follow my method, reference may be had to the accompanying drawing which are hereunto annexed in which:

Fig. 1 is a side elevation with part of the device 40 broken away and the same being shown in section;

Fig. 2 is a section on the line 2—2 of Fig. 1; Fig. 3 is a section of the same device on the line 3—3 of Fig. 1; and

45 Fig. 4 is a plan view of the master key plate. Similar reference numerals refer to similar parts throughout the entire specification.

As shown in the drawing, a slotting device is shown, but as stated, it is only for illustrative purposes. In this device is a base which supports a frame 1, the frame is provided with an anvil 2. This anvil is preferably provided on the upper surface with a die plate 3. A slot 4 being formed along one edge of the anvil and die plate.

50 55 The extreme edge of the die plate 3 is provided

with an abutment 5 against which the master key plate and card abut.

The frame 1 is provided with uprights 6. Secured to these uprights 6 is a spring plate 7 which is provided with a downward projection 8, a slot 9 being formed therein into which the ends of springs 10 may be formed. The projection 8 is spaced from the anvil 2 as indicated at 11 to permit the insertion of the master key plate and card.

10 A plurality of slotting punches 12 are provided, the number of the same corresponding to the number of perforations in the Perkins card which is to be slotted. As illustrated, they are pivotally mounted on a pin 13, one arm of the spring 10 is wound around this pin. The outer end 4 of the spring is wound around a projection 15 which extends upwardly from the punch body. It will be clear that this arrangement will serve 20 to hold the punches suspended above but being pivotally mounted, engagement of the lower part will tend to tilt the punch so that it will be inoperative.

A yoke 17 provided with a handle 18 is secured to the frame 1, a spring 19 being provided to 25 hold it normally in horizontal position. On this yoke I mount a cross bar 21 which engages the punches and which actuates the same when the handle 18 is depressed.

It will be clear to persons skilled in the art 30 that if the handle 18 is depressed it will project all of the dies downwardly, the card will be notched by all of the punches. This however is not the practice of my method which is as 35 stated to slot a pattern of notches referring to a single classification.

It is obvious that if a master plate is cut with a pattern of notches which refers, for example, to a specific number, say 52316, that insertion of the master plate will render those punches which are contacted by the points on the master plate inoperative, so that by placing a card which is to have the required pattern of notches cut or slotted therein beneath the key plate and then actuating the handle 18, only those punches which will be required to notch the desired pattern will be depressed by the movement of the handle 18.

It will also be clear to persons skilled in the art 50 that although I have shown the specific type of card slotted illustrated and described in my Patent No. 2,144,412, that any number of devices for example, such as referred to above will be constructed which will employ my method and as 55

stated the drawing is furnished merely for illustrative purposes.

Having described my invention what I regard as new and desire to secure by Letters Patent is:

1. The method of preparing cards and the like for sorting comprising the following steps, punching a plurality of holes adjacent one or more edges of a card, providing a plurality of means to notch one or more edges of said card, rendering certain 10 of said notching means inoperative, actuating said notching means thereby notching said card with a predetermined pattern of notches in one edge of said card.

2. The method of preparing cards and the like 15 for sorting comprising the following steps, punching a plurality of holes adjacent one or more edges of a card, providing means to notch one or more edges of said card, notching a master plate 20 of harder material than the card to be notched with a pattern of notches on one edge, inserting said plate in said notching means thereby rendering certain of the notching means inoperative, actuating said notching means thereby notching said card with a predetermined pattern of notches 25 in one edge of said card.

3. The method of preparing cards and the like for sorting comprising the following steps, punching a plurality of holes adjacent one or more edges of a card, providing means to notch one or more edges of said card, inserting means of harder material than the card to be notched in said notching means whereby certain of said notching means are rendered inoperative, actuating said notching means thereby notching said card with a predetermined pattern of notches in one edge of said 10 card.

4. The method of preparing cards and the like for sorting comprising the following steps, punching a plurality of holes adjacent one or more edges of a card, preparing a master card of harder 15 material than the card to be notched with a predetermined pattern of notches on one edge, providing means to punch notches in the edge of said card, rendering certain of said punches inoperative whereby to punch a predetermined pattern 20 of notches in the edge of the card.
